[57] CLAIM

The ornamental design for a watering attachment for flower pots or the like, as shown and described.

DESCRIPTION

FIG. 1 is a front perspective view of a watering attachment for flower pots or the like showing my new design;

FIG. 2 is a rear perspective view thereof;

FIG. 3 is a bottom view thereof;

FIG. 4 is a top view thereof;

FIG. 5 is a right side view thereof, the left being a mirror image;

FIG. 6 is a rear view of a second embodiment of the design of FIG. 1 the only difference being the change in arrangement and numbers of the apertures and the sloping of the upper side walls;

FIG. 7 is a rear view of a third embodiment of the design of FIG. 1, the only difference being the increase in length, the change in arrangement and numbers of the apertures and the sloping of the upper side walls.

FIG. 1

FIG. 4

FIG. 5

FIG. 6

FIG. 2

FIG. 7

FIG. 3
